UNITED STATES PATENT OFFICE.

WILLIAM H. JAMOUNEAU, OF NEWARK, NEW JERSEY.

DESIGN FOR A SPOON, &c.

SPECIFICATION forming part of Design No. 20,967, dated July 28, 1891.

Application filed May 9, 1891. Serial No. 392,246. Term of patent 7 years.

To all whom it may concern:

Be it known that I, WILLIAM H. JAMOUNEAU, a citizen of the United States, residing at Newark, in the county of Essex and State 5 of New Jersey, have invented and produced a new and original Design for Handles for Spoons, Forks, or other Articles technically known to the trade as "Flat Ware;" and I do hereby declare the following to be a full, clear, 10 and exact description of the invention, such as will enable others skilled in the art to which it appertains to make and use the same, reference being had to the accompanying drawing, and to letters of reference marked 15 thereon, which form a part of this specification.

The figure of the drawing is a front plan of a spoon of my improved design, of which the following is a specification, the one figure 20 being deemed sufficient to fully illustrate the same.

The leading feature of the design consists in the spoon or fork handle having an inclined bell-shaped ornamentation thereon at 25 the end opposite the bowl or prongs.

In said drawing, *a* indicates the bowl of the spoon, *b* the broad end of the handle opposite said bowl, and *c* the narrow shank of the handle. The broad portion *b* is ornamented with the representation of a cracked bell *e*, 30 attached to a beam *d*, from which latter appears to depend the representation of a rope *f*, which also is represented as being twisted on the narrow shank. The bell-shaped ornament appears to hang at an angle to the longitudinal axis of the handle and at the lower end lies beyond the normal edge line of the spoon, as shown.

What I claim is—

The design for a fork, spoon, or other flat- 40 ware handle, having the shape and ornamentation as herein shown and described.

In testimony that I claim the foregoing I have hereunto set my hand this 7th day of May, 1891.

WILLIAM H. JAMOUNEAU.

Witnesses:

CHARLES H. PELL,
OSCAR A. MICHEL.
